United States Patent Office

Des. 197,007
Patented Dec. 3, 1963

197,007

REFUSE HOLDER

John C. Brighton, % Arvis Industries, Inc.,
Columbus, Ind.

Filed Oct. 8, 1962, Ser. No. 72,035

Term of patent 14 years

(Cl. D14—3)

Fig. 5.

Fig. 6.

Fig. 7.

Fig. 8.

FIG. 1 is a perspective view of a refuse holder embodying my new design;

FIG. 2 is a rear elevation thereof;

FIG. 3 is a front view thereof, but showing the lid and doors in open position;

FIG. 4 is a plan view thereof;

FIG. 5 is a perspective view of a modified form of the refuse holder shown in FIG. 1, and differing therefrom in the omission of the wheels, axle and handle grips;

FIG. 6 is a rear elevation of the refuse holder shown in FIG. 5;

FIG. 7 is a front view of the refuse holder shown in FIG. 5, but showing the lid and doors in open position; and

FIG. 8 is a plan view of the refuse holder shown in FIG. 5.

The dominant features of my design are shown in full lines.

I claim:

The ornamental design for a refuse holder, as shown and described.
